SLOPE MEASURING INSTRUMENT

William B. Wade, 1730 Garden St., Santa Barbara, Calif.

Filed Jan. 13, 1964, Ser. No. 78,183

Term of patent 14 years

(Cl. D52—6)

FIG. 1

FIG. 2

FIG. 3

FIG. 4

FIG. 1 is a front elevational view of a slope measuring instrument, with portions of the glass window broken away to illustrate the features on the face of the instrument, showing my new design.

FIG. 2 is a top view of FIG. 1.

FIG. 3 is an end view of FIG. 1.

FIG. 4 is an isometric view thereof.

The undisclosed end of the instrument is substantially the same as the end shown, and the rear thereof, except for the knob and washer, is substantially plain in appearance.

I claim:

The ornamental design for a slope measuring instrument, as shown and described.
